UNITED STATES PATENT OFFICE.

WILLIAM FREDERICK WRIGHT, OF EDINBURGH, SCOTLAND.

DESIGN FOR A BOTTLE.

Application filed November 30, 1925, Serial No. 15,588, and in Great Britain July 31, 1925. Term of patent 14 years.

To all whom it may concern:

Be it known that I, WILLIAM FREDERICK WRIGHT, a British subject, residing at 31 Albany Street, Edinburgh, Scotland, North Britain, have invented a new and ornamental Design for Bottles, of which the following is a specification, reference being had therein to the accompanying drawing.

Fig. 2 is another elevation of the same bottle and

Fig. 3 is a top view of the same bottle.
I claim:—

The ornamental design for a bottle substantially as herein shown and described.
In testimony whereof I affix my signature.

WILLIAM FREDERICK WRIGHT.
